Primary Examiner—Ian Simmons

(73) Assignee: **Industrie Borla Spa** (IT)

(74) Attorney, Agent, or Firm:—TraskBritt

(**) Term: **14 Years**

(57) CLAIM

(21) Appl. No.: **29/134,603**

The ornamental design for a drip chamber with four outer axial ribs for infusion or transfusion medical lines, as shown and described.

(22) Filed: **Dec. 22, 2000**

DESCRIPTION

(30) Foreign Application Priority Data

Aug. 3, 2000 (IT) TO00000189

(51) LOC (7) Cl. **24-02**

FIG. 1 is a bottom perspective view of a drip chamber with four axial ribs for infusion or transfusion medical lines showing my new design;

(52) U.S. Cl. **D24/112**

FIG. 2 is a top perspective view thereof;

(58) Field of Search **D24/112, 121,**

FIG. 3 is a left side elevational view thereof;

D24/108; 128/DIG. 13, DIG. 12; 604/251,

FIG. 4 is a right side elevational view thereof;

403, 411, 412, 257, 122

FIG. 5 is a bottom plan view of FIG. 1; and,

(56) References Cited

FIG. 6 is a top plan view thereof.
